UNITED STATES PATENT OFFICE.

HOWARD D. COLMAN, OF ROCKFORD, ILLINOIS

KNOT-TYING IMPLEMENT.

SPECIFICATION forming part of Letters Patent No. 707,826, dated August 26, 1902.

Application filed October 23, 1900. Serial No. 34,069. (No model.)

To all whom it may concern:

Be it known that I, HOWARD D. COLMAN, a citizen of the United States, residing at Rockford, in the county of Winnebago and State 5 of Illinois, have invented certain new and useful Improvements in Knot-Tying Implements, of which the following is a specification.

The object of this invention is the production of a hand-operated implement adapted to tie that form of knot known as the "weaver's" knot.

In the embodiment herein shown of this invention the tying mechanism is intended to be worn constantly on the left hand of the operator and its parts to be actuated by a pivoted lever adapted to be engaged by the thumb of said hand. In said operation the first thread is wound helically about a bifurcated 20 spindle by the rotation of the latter, and the necessary loops of the knot are formed in said thread by a tumbler-finger passing through the bifurcation of the winding-spindle and turning a somersault as it passes. At the end 25 of its movement this tumbler-finger stands with the first thread looped over its end and with a jaw open to receive the second thread of the knot, which the next and final movement of the mechanism causes it to shear off 30 and clamp, after which the knot is stripped from the winding-spindle of the implement by the rotation of the spool on the spooling mechanism. It will thus be seen that the loops necessary for the production of the knot 35 are formed in one thread and pulled over the second thread while the latter is held by the mechanism.

In the accompanying drawings, Figure 1 is a side elevation of a knot-tying implement 40 embodying the features of my invention. Its parts are represented to be in the first or normal position, ready to receive the "first" thread in forming the knot. Fig. 2 is an enlarged front elevation of said mechanism 45 looking in the direction of the arrow 2 in Fig. 1, the parts remaining in the normal position. Fig. 3 is a top plan view of the implement, its parts being in the normal position. Fig. 4 is a vertical section through the mechanism on 50 dotted line 4 4 of Fig. 2 looking in the direction of the arrow, the thumb-lever, however, having been depressed through its full move-

ment and the mechanism moved accordingly. This position is hereinafter designated as the "third" position of the mechanism. Fig. 5 55 is a vertical section on dotted line 5 5 of Fig. 2 looking in the direction of the arrow. Fig. 6 is a vertical section on dotted line 6 6 of Fig. 3, the mechanism being in a position incident to the depression of the thumb-lever 60 through about one-half its movement, hereinafter designated as the "second" position of the mechanism. Fig. 7 is a section on dotted line 7 7 of Fig. 2 looking in the direction of the arrow, the thumb-lever having been 65 depressed slightly to move the tension-arm D⁷, which latter is represented in its lowest position. Fig. 8 is a central section through the bifurcated winding-spindle on dotted line 8 8 of Fig. 6. Fig. 9 is a side elevation of 70 said winding-spindle as shown in Fig. 8 looking in the direction of the arrow in said Fig. 8. Fig. 10 is a side elevation of the tumbler-finger and its immediate connections, said finger being represented as in the third position. Fig. 11 is a perspective view of the 75 knot-forming mechanism in its first or normal position, showing the first thread placed in position to be acted upon. Fig. 12 is a similar view of the same parts after said thread 80 has been cut off and clamped by the shearing and clamping jaw of the winding-spindle and said spindle has made a quarter-revolution. Fig. 13 is a similar view of said mechanism 85 in the second position, showing the winding-spindle at rest after having been rotated one and one-quarter revolutions from the first position, also showing the tumbler-finger as entering the bifurcation of said winding-spindle between the loops of the thread wound 90 thereon. Fig. 14 is a similar view showing the parts of the mechanism in the third position—to wit, the relative positions assumed by the mechanism at the end of the downward movement of the thumb-lever, the tumbler-finger having passed through the bifurcation of the winding-spindle, turning a complete somersault therein, looping the thread wound about said spindle, and drawing said 95 loop outward and retaining it on the end of said finger. The shearing and clamping jaw of said finger stands open in this position of the mechanism ready to receive the second thread, which is represented in this figure as 100

being in place in said jaw. Fig. 15 shows the mechanism after the next movement—to wit, an upward movement of the thumb-lever, which causes the shearing and clamping jaw 5 of the tumbler-finger to shear and clamp the second thread. This is the fourth and final position of the mechanism, after which the knot is ready to be drawn from the winding-spindle. This latter may be accomplished by 10 grasping the end of the first thread in the right hand and drawing upward thereon, but in practice is done by releasing the winding-spool of the warping mechanism to action. Fig. 16 represents the withdrawal of the knot 15 from said winding-spindle. Fig. 17 shows the knot formed, the ends of the thread still being retained in the clamping-jaws of the winding-spindle and the tumbler-finger. Fig. 18 illustrates the weaver's knot, showing the direction and position of the threads as the 20 knot is formed by the mechanism and before the loops of said knot are tightened. Fig. 19 is a view of a weaver's knot, illustrating the relative positions of the loops and the direction of the threads when the knot is drawn 25 tight.

Like letters of reference indicate corresponding parts throughout the several views.

To assist in a ready comprehension of this 30 knot-tier, the mechanism may be said to assume four principal positions, to wit:

The first or normal position. (Illustrated in Figs. 1, 2, 3, 5, and 11.)

The second position, wherein the first thread 35 has been helically wound upon the winding-spindle and said spindle stands ready for the passage of the tumbler-finger through its bifurcated end, as indicated in Figs. 6, 8, 9, and 13.

The third position, wherein the tumbler-finger 40 has passed through the bifurcated end of the winding-spindle and stands with the first thread looped over its free end and with its shearing and clamping jaw open to receive the 45 second thread. In this position the thumb-lever is depressed to its lowest point. The third position is indicated in Figs. 4, 10, and 14.

The fourth and final position, which differs from the third only in that the shearing 50 and clamping jaw of the tumbler-finger has been closed, cutting off the second thread and clamping the short end thus made and said finger moved back toward the winding-spindle in position to permit the formed knot to 55 be stripped from the mechanism and tightened. The fourth position is indicated in Figs. 15, 16, and 17.

The thread first presented to the mechanism to be wound about the winding-spindle 60 and looped by the tumbler-finger may be designated as the "first" thread, and the thread placed in the open jaw of the tumbler-finger when the mechanism is in the third position may be called the "second" thread. 65 In the operation of the implement the winding-spindle mechanism is first actuated, it finishing its work and coming to rest before

the tumbler-finger mechanism begins its operations.

In the construction of this implement I provide a framework A, having the handle portion A', with the strap A² for securing the implement to the hand of the operator. This strap is made adjustable in length for hands of different sizes by means of the buckle A³. Between the handle A' and the framework A is the sleeve A⁴, extending from one side of said frame A. Just above the sleeve A⁴ the frame A assumes a rectangular outline, and the upper end of the frame is provided with a guide-arm A⁵ for the thread first presented to the mechanism, also with a curved guide-wire A⁶ for directing the second thread when the latter is presented to the mechanism. Said frame has a shoulder A⁷ for a purpose to be hereinafter mentioned.

A winding-spindle B is rotatably mounted in the framework A. The upper end of this spindle is bifurcated, comprising the two fingers B' and B'', having between them the opening B³. The finger B'' has a longitudinal slot B⁴, provided with a fixed shearing-jaw B⁵. This slot B⁴ also contains a pivoted shearing-jaw B⁶, adapted to shear with one of its forward edges and to clamp with its other forward edge, said jaw being free to move in the space between the fixed shearing-jaw B⁵ and the side of said longitudinal slot B⁴, so that a thread placed in said pivotal jaw B⁶ when opened will by the closing thereof be cut off between said shearing-jaws B⁵ and B⁶ and clamped between the jaw B⁶ and the side of the longitudinal slot B⁴. The shearing and clamping jaw B⁶ has an integral extension B⁷ rearward of its supporting-pivot, and this extension is provided with an elongated opening B⁸, intended to be engaged by a pin adapted to operate said jaw B⁶, as will be later described herein. The portion of the winding-spindle located between its bearings in the rectangular portion of the supporting-frame has a spiral cam-groove B⁹ formed in its peripheral surface. A collar B¹⁰ surrounds said spindle and is provided with a pin B¹¹ for entering said cam-groove B⁹, by which connection said collar is raised or lowered when said spindle is rotated. A guide-rod B¹² lies parallel with said winding-spindle in suitable bearings in the rectangular portion of the frame A and is capable of a longitudinal movement in said bearings. The upper end of this guide-rod is bent in U form to receive the thread intended to be wound around the spindle B by the rotation of the latter. The lower end of the guide-rod B¹² is fixed with 125 relation to the collar B¹⁰, and, as will be seen, a rotation of the spindle B will produce a longitudinal movement of the guide-rod B¹², whereby the first thread is fed onto said spindle helically as the latter is rotated. B¹³ is 130 a pinion, and B¹⁴ a delay-shoe, both fixed on the winding-spindle B. A curved guide B¹⁵ is secured to the rectangular portion of the frame A in such a position that the upper

edge of said guide will enter the elongated opening B⁸ in the rear end of said shearing and clamping jaw B⁶ when the winding-spindle is rotated in order to hold said jaw in a closed position.

A shaft C is journaled within the sleeve A⁴ of the supporting-frame A and has fixed thereon the blind sector-gear C', having the teeth C², adapted to mesh with those of the pinion B¹³, also having two delay-flanges C³ and C⁴, adapted to be contacted by the delay-shoe B¹⁴ of the winding-spindle B. This sector-gear C' has pivoted to its side a locking-lever C⁵, the rear end of said lever being held elevated by the spring C⁶ in order to cause the rear end of said lever to engage the shoulder A⁷ of the supporting-frame A to stop the parts of the mechanism in the fourth position. The sector-gear C' is also provided with a pin C⁷, adapted to enter the elongated opening B⁸ of the shearing and clamping jaw B⁶, and when the mechanism is in the first or normal position to open said shearing and clamping jaw, closing said jaw at the beginning of the operation of the mechanism. The sector-gear C' is also provided with a stud C⁸, the purpose of which will be hereinafter mentioned.

D is a thumb-lever forked at its forward end to receive the thumb of the operator. Its rear end is in clamp form, surrounding and frictionally engaging the hub D' of the sector-cam D². This cam is provided with an elongated opening D³, adapted to receive the stud C⁸ of the sector-gear C'. The hub D' is mounted loosely upon the shaft C, whereby it will be seen that the thumb-lever and sector-cam being fixed together have a slight oscillatory movement with relation to the sector-gear C'. The peripheral face of said sector-cam D² is in cam form. At its forward end it has a pocket D⁴ and at its rear end a sudden declivity D⁵, the peripheral surface D⁶ of the cam gradually descending toward its rotatable center from said pocket D⁴ to the crest of said declivity D⁵.

A tension-arm D⁷ for the first thread has a pivotal connection with the upright portion of the supporting-frame A. Its free end is held upraised by a coil-spring D⁸; but its movement is governed by a roller-stud D⁹, riding upon the peripheral surface of the sector-cam D². When the thumb-lever D is in its upraised position incident to the first position of the mechanism, the roller-stud D⁹ of the tension-lever lies in the pocket D⁴ of the sector-cam D². A downward movement of said thumb-lever, producing an upward movement of the sector-cam D², moves said roller-stud D⁹ in said pocket D⁴ and causes a considerable downward movement of the forward end of the tension-arm D⁷. This position is illustrated in Fig. 7 of the drawings. A continued downward movement of the thumb-lever carries the roller-stud out of the pocket and into contact with the peripheral cam-surface D⁶ of the sector-cam D². This cam-surface permits a slow upward movement of the ten-

sion-lever D⁷, (to yield the thread to the rotating winding-spindle B,) and as soon as the roller-stud D⁹ reaches the declivity D⁵ of the sector-cam D² the forward end of the tension-lever is permitted to rise rapidly.

A sector-frame E is rigidly secured by the clamp E' to the outer end of the sleeve A⁴ of the frame A. This sector is provided with the gear-teeth E² and the peripheral delay-surface E³. On the outer end of the shaft C, adjacent to said sector E, an arm F is fixed. The free end of this arm is provided with the frame F' and has rotatably mounted therein the shaft F², with the pinion F³ and the delay-shoe F⁴ fixed on said shaft. The teeth of the pinion F³ are adapted to mesh with the gear-teeth E² and the delay-shoe F⁴ to slide in contact with the peripheral delay-surface E³ of the sector E.

The tumbler-finger G and its integral supporting-arm G' form a yoke of rectangular form, and said arm is provided with a hub G² and is affixed by said hub to the end of the shaft F². The tumbler-finger G has a shearing-jaw G³ fixed on its inner side at a little distance from said finger in order to leave room between said fixed shearing-jaw G³ and said finger for the shearing and clamping jaw G⁴, pivoted to said fixed jaw G³. This pivoted shearing and clamping jaw G⁴, like the tumbler-finger, is, with its integral supporting-arm G⁵, substantially of rectangular yoke form. The arm G⁵ of said shearing and clamping jaw has an elongated opening G⁶ at its rotatable center, through which the shaft F² passes, and at one side of its said central opening G⁶ is provided with a stud G⁷, adapted to engage a circular channel G⁸, formed in the frame F'. This circular channel G⁸ is provided with an outwardly-extending pocket G⁹, into which the stud G⁷ passes when the shearing and clamping jaw G⁴ opens on its pivot, and to throw said stud G⁷ into said pocket G⁹ and cause said jaw G⁴ to open I provide a pivotal connection between the hub G² and the arm G⁵ of the shearing and clamping jaw G⁴, comprising the pin G¹⁰, which enters an opening in said arm. The purpose of this channel G⁸ is to prevent the opening of the shearing and clamping jaw G⁴ except in the third position of the mechanism, when the stud G⁷ enters the pocket G⁹.

In use the implement hereinbefore described is worn upon the left hand of the operator. When the ends of two threads are to be tied together, the parts of the mechanism are thrown into the first or normal position. One of said threads is grasped by the right hand of the operator and laid in the groove of the guide-arm A⁵, in the U depression in the upper end of the guide-rod B¹², and into the open shearing and clamping jaw B⁶ of the winding-spindle B. A slight downward movement of the thumb-lever D rocks the sector-cam upon the shaft C through the length of the elongated opening D³ and depresses the tension-arm D⁷, (see Fig. 7,) the latter by its downward

movement forming a bight in said thread between the guide-arm A⁵ and the guide-rod B¹², taking slack for said bight from the end of the thread held in the hand of the operator. This considerable downward movement of the tension-arm is caused by the pocket D⁴ of the sector-cam D², which the roller-stud D⁹ of the tension-arm D⁷ engages at the first part of the downward movement of the thumb-lever D. A continued depression of said thumb-lever D oscillates the shaft C and the sector-gear C', fixed on said shaft. In the normal position of the mechanism the delay-shoe D¹⁴ of the winding-spindle lies in contact with the delay-flange C⁸ of the sector-gear C', and the pin C⁷ lies in the opening B⁸ of the shearing and clamping jaw B⁶, holding said jaw open. As soon as said sector-cam D² has been oscillated through the length of the elongated opening D³ and the sector-gear C' is given movement the pin C⁷ moving away from the winding-spindle B rocks the shearing and clamping jaw on its pivot, closing said jaw and shearing and clamping said first thread. The instant this is accomplished the gear-teeth C² of the sector-gear C' engage the teeth of the pinion D¹³, and the winding-spindle is rotated. With the rotation of the spindle the tension-arm D⁷ rises slowly to give sufficient slack thread to the winding-spindle, and the guide-rod B¹² is caused to move downward by reason of its collar-and-pin engagement with the cam-groove B⁹ in the winding-spindle B in order to direct the thread helically upon the upper end of said spindle. The gear-teeth C² of the sector-gear C' are sufficiently numerous to rotate the winding-spindle B through one and one-fourth revolutions, said spindle coming to rest with its delay-shoe D¹⁴ in contact with the delay-flange C⁸ of the sector-gear C', with the elongated opening B⁸ of the shearing and clamping jaw B⁶ in engagement with the curved guide B¹⁵ and its opening B³ properly disposed to permit the passage of the tumbler-finger G therethrough. The tumbler-finger G, which by reason of its arm connection with the shaft C has been caused to approach the winding-spindle, now enters, point first, the opening B³ in the upper end of said spindle, passing over the strand of thread on the near side of said spindle and between the two strands on the opposite side of the spindle. At this moment and while the tumbler-finger G is within said opening B³ the pinion F³ engages the teeth E² of the sector-frame E and the tumbler-finger turns a forward somersault, emerging from the opening B³ in an inverted position, holding the portion of the thread last wound upon the spindle looped over the end of the finger, having pulled said thread through the upper loop formed by winding the thread about the upper end of said spindle. During the somersault of the tumbler-finger G the shearing and clamping jaw G⁴ thereof is held closed by the stud G⁷ sliding in the circular channel G⁸, but at a point near the end

of the movement of the tumbler-finger said stud passes into the pocket G⁹, and the slight further movement of the tumbler-finger G opens the shearing and clamping jaw G⁴ by reason of the pivotal connection (the pin G¹⁰) between the hub G² and the arm G⁵ of said shearing and clamping jaw G⁴. This places the mechanism in the third position (illustrated in Fig. 14 of the drawings) ready to receive the second thread, which is drawn into the open shearing and clamping jaw G⁴ of the tumbler-finger G, said thread being guided to said jaw by the curved guide-wire A⁶. When the second thread is in place in said jaw G⁴, the thumb-lever D is raised slightly until the rear end of the locking-lever C⁵ engages the shoulder A⁷ of the supporting-frame A. This movement of the thumb-lever D closes the shearing and clamping jaw G⁴, cutting off and clamping the second thread and placing the mechanism in the fourth and final position, as shown in Figs. 15, 16, and 17 of the drawings. The knot formed upon the winding-spindle B and the tumbler-finger G is now ready to be pulled off and tightened, which is done by stripping the first thread upward from the mechanism. The knot is tightened as the short ends of the two threads are pulled from the two clamping and shearing jaws B⁶ and G⁴. The forward end of the locking-lever C⁵ extends to a point near the thumb-lever D, and the thumb of the operator raises said locking-lever without being removed from the thumb-lever when it is desirable to restore the mechanism to the normal position.

I claim as my invention—

1. In a knot-tying implement, in combination, means for forming a loop in a thread; which means comprises a rotatable winding-spindle; means for passing a bight of said thread through said loop; and means for introducing a second thread into said bight. 105
2. In a knot-tying implement, in combination, means for forming a loop in a thread; which means comprises a rotatable winding-spindle; means for passing a bight of said thread through said loop; and means for holding a second thread in such position that the bight thus formed may be pulled over said second thread. 110
3. In a knot-tying implement, in combination, means for looping a thread in helical form; which means comprises a rotatable winding-spindle and a movable thread-guide; means for passing a bight from one of the windings of the helix inwardly through the central loop of the latter; and means for introducing a second thread into said bight. 120
4. In a knot-tying implement, in combination, mechanism for forming a loop in a thread; which mechanism comprises a rotatable bifurcated winding-spindle; means for passing a bight of the thread through the formed loop; and means for introducing a second thread into said bight. 130
5. In a knot-tying implement, in combina-

tion, a winding-spindle for forming a loop in a thread; a shearing and clamping jaw pivotally mounted on said spindle; means for passing a bight of said thread through the formed loop; and means for introducing a second thread into said bight.

6. In a knot-tying implement, in combination, a winding-spindle having an opening therein; a shearing and clamping jaw pivotally mounted on said spindle; means for rotating said spindle and winding a thread thereon; means adapted to pass through the opening in said spindle, for passing a bight of said thread through the loop formed by winding it about said spindle; and means for holding a second thread in such position that the bight thus formed may be pulled over said second thread.

7. In a knot-tying implement, in combination, a winding-spindle having an opening therein, also having a shearing and clamping jaw; means for rotating said spindle and winding a thread thereon; means adapted to pass through the opening in said spindle, for passing a bight of said thread through the loop formed by winding said thread about the spindle; and a shearing and clamping jaw for holding a second thread in such position that the bight thus formed may be pulled over said second thread.

8. In a knot-tying implement, in combination, means for forming a loop in a thread; which means comprises a rotatable winding-spindle having a shearing and clamping jaw; a finger adapted to pass a bight of said thread through said loop; and means for introducing a second thread into said bight.

9. In a knot-tying implement, in combination, means for forming a loop in a thread, said means comprising a shearing and clamping jaw; a tumbler-finger adapted to pass a bight of said thread through said loop; and means for introducing a second thread into said bight.

45 10. In a knot-tying implement, in combination, means for forming a loop in a thread, said means comprising a shearing and clamping jaw; a tumbler-finger adapted to pass a bight of said thread through said loop; and means for holding a second thread in such position that the bight thus formed may be pulled over said second thread.

11. In a knot-tying implement, in combination, means for forming a loop in a thread, said means comprising a shearing and clamping jaw; a tumbler-finger adapted to pass a bight of said thread through said loop; and a clamping-jaw for holding a second thread in such position that the bight thus formed may be pulled over said second thread.

12. In a knot-tying implement, in combination, means for forming a loop in a thread; a tumbler-finger adapted to pass a bight of said thread through said loop; and a shearing and clamping jaw on said tumbler-finger, for cutting off a second thread, and for hold-

ing it in such position that said bight may be pulled over said second thread.

13. In a knot-tying implement, in combination, a winding-spindle having an opening therein; means for rotating said winding-spindle; a tumbler-finger adapted to pass through the opening in said winding-spindle; means for turning said tumbler-finger; and means for holding a second thread adjacent to said winding-spindle.

14. In a knot-tying implement, in combination, a winding-spindle having an opening therein; a shearing and clamping jaw on said spindle; means for rotating said spindle; a tumbler-finger adapted to pass through the opening in said spindle; means for turning said tumbler-finger; and a shearing and clamping jaw on said finger.

15. In a knot-tying implement, in combination, a winding-spindle having an opening therein; a shearing and clamping jaw on said spindle; a thread-guide adapted to have a longitudinal movement with relation to said spindle while the same is being rotated; a tumbler-finger adapted to pass through the opening in said spindle; means for turning said tumbler-finger; and a shearing and clamping jaw on said tumbler-finger.

16. In a knot-tying implement, in combination, a winding-spindle having an opening therein; a shearing and clamping jaw on said spindle; a thread-guide adapted to have a longitudinal movement with relation to said spindle during the rotation of the latter; a tension-arm; a tumbler-finger adapted to pass through the opening in said spindle; a gear for turning said tumbler-finger; and a shearing and clamping jaw on said finger.

17. In a knot-tying implement, in combination, a winding-spindle having an opening therein; a shearing and clamping jaw on said spindle; intermeshing gear for rotating said spindle; said spindle also having a cam-groove; a thread-guide adapted to be actuated by said grooved cam; a tension-arm; a cam for actuating said tension-arm; a tumbler-finger adapted to pass through said opening in said spindle; a gear for turning said tumbler-finger; and a shearing and clamping jaw on said finger.

18. In a knot-tying implement, in combination, a winding-spindle having an opening therein, and a cam-groove; a shearing and clamping jaw on said spindle; a pinion and a delay-shoe for the spindle; a sector-gear; gear-teeth and two delay-flanges on said sector; a thread-guide adapted to be actuated by said grooved cam; a tumbler-finger adapted to pass through the opening in said spindle; means for turning said tumbler-finger; and a shearing and clamping jaw on said finger.

19. In a knot-tying implement, in combination, a winding-spindle having an opening therein; a shearing and clamping jaw on said spindle; said spindle also having a pinion and a delay-shoe thereon, and a cam-groove

therein; a guide-arm for the thread, adapted to be moved by said grooved cam; a sector-gear having gear-teeth for said pinion, and two delay-flanges for said delay-shoe; a tension-arm; a cam for actuating said tension-arm; a thumb-lever for moving said sector and said cam; a projection on the sector-gear for opening and closing the shearing and clamping jaw; a tumbler-finger adapted to 5 pass through the opening in said spindle; means for turning said tumbler-finger; and a shearing and clamping jaw on said finger.

20. In a knot-tying implement, in combination, a winding-spindle having an opening 15 therein and a cam-groove; said spindle also having a pinion, a delay-shoe, and a shearing and clamping jaw; a fixed guide for holding said shearing and clamping jaw closed; a sector-gear having gear-teeth for said pinion and 20 two delay-flanges for said delay-shoe, also having a projection for opening and closing said shearing and clamping jaw; a shaft for said sector-gear; a sector-cam loosely mounted on said shaft, but movably connected with 25 said gear-sector; a tension-arm adapted to be actuated by said sector-cam; a thread-guide adapted to be moved by the grooved cam of said winding-spindle; a thumb-lever having a rigid connection with said cam-sector; a 30 tumbler-finger adapted to pass through the opening in said spindle; means for turning said tumbler-finger; and a shearing and clamping jaw on said finger.

21. In a knot-tying implement, in combination, 35 a winding-spindle having an opening

therein; means for rotating said spindle; a tumbler-finger adapted to pass through the opening in said spindle; a supporting-shaft for said tumbler-finger; a pinion and a delay-shoe on said shaft; a fixed sector having gear-teeth for said pinion, and a peripheral delay- 40 surface for said delay-shoe; and a shearing and clamping jaw for said tumbler-finger.

22. In a knot-tying implement, in combination, a winding-spindle having an opening 45 therein; means for rotating said spindle; a shaft; a thumb-lever on said shaft; an arm fixed with relation to said shaft; a frame on said arm; a tumbler-finger adapted to pass through the opening in said spindle; a shaft 50 for said tumbler-finger; said frame being provided with a channel concentric with the bearing for said tumbler-finger, said channel having a pocket near its end; a pinion and a delay-shoe on said tumbler-finger shaft; a 55 fixed sector having gear-teeth for said pinion and a peripheral delay-surface for said delay-shoe; a shearing and clamping jaw having a pivotal connection with said tumbler-finger, also having an integral arm; a stud on said 60 arm, adapted to engage the concentric channel in said frame; and a pivotal engagement between said tumbler-finger and said arm, whereby the stud on said arm is thrown into the pocket in said channel to open said shearing and clamping jaw.
